LOOM CHECK STRAP

John C. Crocker, Ware Shoals, S. C.

Application August 24, 1944, Serial No. 550,948

8 Claims. (Cl. 139—165)

This invention relates to an improved check strap for looms which has overlapped ends at one or both ends thereof so as to give double wearing qualities and at the same time permits the use of short pieces of leather, whereas heretofore check straps have been composed of one long piece of leather which is very expensive because only a small portion of a cowhide has leather of sufficient thickness and length to provide the elongated strips which have heretofore been in conventional use. By the use of short pieces of leather and overlapping the same at one or both ends, a check strap can be provided which will have much longer wear than the conventional check strap made of one long piece of leather but will be much less expensive on account of being able to use a large portion of the cowhide which heretofore has been unsuitable for use as check straps.

It is an object of this invention to provide a check strap for looms made of a piece of leather overlapped at one or both ends to provide a double thickness of wearing surface at the point where the picker stick engages the check strap.

It is another object of this invention to provide a check strap made of two pieces of leather and overlapping at one of the ends and has an eccentric wearing plug, preferably made of leather, disposed between the other ends so that the eccentric wearing plug can be adjusted as to position to regulate overall length of the interior portion of the check strap from one end to the other.

Some of the objects of the invention having been stated, other objects will appear as the description proceeds when taken in connection with the accompanying drawings in which

Figure 1 is a side elevation of one end of the lay of a loom showing my invention applied thereto;

Figure 2 is a bottom plan view, partly in section, looking upward from below Figure 1;

Figure 3 is a view similar to Figure 2, but showing the check strap of double thickness;

Figure 4 is a view similar to Figure 1, but showing another form of check strap;

Figure 5 is a bottom plan view looking upward from the lower edge in Figure 4;

Figure 6 is a view similar to the structure of the check strap shown in Figure 5, but showing it of double thickness.

Referring more specifically to the drawings the numeral 10 indicates one end of the lay of a loom having a race plate 11 and box front 12, there being a binder also on the top of the plate 11, 55

but this binder is behind the box front and is not shown, and between the binder and box front 12 a shuttle 13 is adapted to be received to cause its nose to strike a picker 14 disposed on an oscillating picker stick 15, which has back and forth movement in a slot 17 in the race plate 11. Secured to the lower and side surfaces of the lay 10 and on each side of the slot 17 are the brackets 20 having a pair of downwardly projecting spaced fingers 21 and 22 and this bracket has outturned lips 23 having a slot 24 therein penetrated by a bolt 25 to which is adjustably secured a horizontal portion 26 of a downwardly depending finger 27, the fingers 21 and 22 and 27 having inturned lips at their lower ends for holding the check strap in its elevated position and the off set relation of fingers 21, 27, and 22 imparts the proper amount of friction to the longitudinal movement of the check strap when stopping the picker stick as it oscillates or swings in both directions. The above described mechanism is conventional in a loom and it is with such a mechanism that my improved check strap is adapted to operate. My improved check strap comprises a pair of 25 short pieces of leather 30 and 31 which are overlapped at one end as at 32 and 33 and secured together by any suitable means such as rivets 34. This gives a double wearing portion to the overlapped ends of the check strap. Between the 30 other ends of the straps 30 and 31 there is secured an eccentric block 35 by means of a bolt 36 and if desired suitable pieces of leather 37 and 38 beveled at their inner ends may be disposed between the eccentric 35 and the ends of the 35 straps 30 and 31. These are secured in position by any suitable means such as rivets 39.

In Figure 3 a slightly modified form of invention from that shown in Figure 2 appears, which has the same structure as the interior portion of 40 that above described but has additional straps 40 and 41 which are overlapped at one end as at 42 and 43 and the rivets 34 are longer than in Figure 2 so as to penetrate the four layers 32, 33, 42, and 43. The form in Figure 3 is better adapted for heavy work as it gives a four-ply construction at the inner end of the check strap.

In Figures 4, 5, and 6 a modified form of invention is shown which has the same construction at the left hand end as that shown in Figures 1, 2, and 3. The check strap in Figures 4 and 5 comprises straps 50 and 51 overlapped at both ends as at 52, 53, 54 and 55 and secured together by rivets 56. In Figure 6, the inner straps 50 and 51 are the same as in Figure 5, but it has

outer straps 57 and 58 which are overlapped at their ends as at 59 and 60 at one end, and 61 and 62 at the other end and longer rivets 56 secure all overlapped ends together. In Figure 6, it is therefore seen that a strap of double thickness on the sides and quadruple thickness at the ends is provided. This not only gives very thick and long lasting wearing portions, but it is to be especially noted that in all forms of the invention short pieces of leather can be utilized instead of the long, rare and expensive pieces of leather heretofore used.

In the drawings and specifications there has been set forth a preferred embodiment of the invention and although specific terms are employed, they are used in a generic and descriptive sense only and not for purposes of limitation, the scope of the invention being defined in the claims.

I claim:

1. A check strap for checking the movement of a picker stick in looms comprising two pieces of pliable material forming two opposed side portions of the check strap and extending the entire length of the check strap, the two pieces of pliable material being overlapped and secured together at one end at the point where the check strap is engaged by the picker stick to provide an end portion having double thickness.

2. A check strap for checking the movement of a picker stick in looms comprising two pieces of pliable material forming two opposed side portions of the check strap and extending the entire length of the check strap, the two pieces of pliable material being overlapped and secured together at one end at the point where the check strap is engaged by the picker stick to provide an end portion having double thickness, and an eccentrically mounted wearing block disposed between the other ends of the pieces of pliable material.

3. A check strap for checking the movement of a picker stick in looms comprising two pieces of pliable material forming opposed side portions of the check strap and extending the entire length of the check strap and being overlapped at each end to form an endless oval member, the overlapped ends being secured together to form a check strap having portions of double thickness disposed at the points where the lug strap is engaged by a picker stick.

4. A check strap for checking the movement of a picker stick in looms comprising a pair of strips of flexible material forming opposed side portions of the check strap and extending the

entire length of the check strap and being overlapped and secured together at one end at the point where the check strap is engaged by the picker stick, and a wearing plug disposed between the other ends of the pieces of flexible material, said wearing plug having an eccentrically disposed hole therethrough and a bolt penetrating the strips and the hole in the wearing plug to secure the strips and the wearing plug together.

5. A check strap for checking the movement of a picker stick in looms comprising two pairs of strips of flexible material forming opposed side portions of the check strap and extending the entire length of the check strap and having all the ends at one end of the strips overlapped and secured together at the point where the check strap is engaged by the picker stick and having a wear plug disposed between their other ends, the wear plug having an eccentrically disposed hole therethrough and a bolt passing through the strips and the hole in the plug to secure the strips to each side of the plug.

6. A check strap for picker sticks in looms comprising two strips of flexible material forming opposed side portions of the check strap and extending the entire length of the check strap and being overlapped at both ends and secured together at the point where the check strap is engaged by the picker stick to provide a continuous check strap having its end portions which are engaged by the picker stick thicker than its side portions.

7. A check strap for checking the movement of picker sticks in looms comprising two pieces of flexible material forming opposed side portions of the check strap and extending the entire length of the check strap and being overlapped at their ends at the point where the same are engaged by the picker stick, said overlapped portions being secured together.

8. A check strap for checking the movement of picker sticks in looms comprising a pair of strips of pliable material forming opposed side portions of the check strap and extending the entire length of the check strap and being overlapped at each end at the points where the check strap is engaged by the picker stick, and a second set of strips of pliable material disposed overlapped at their ends, and a common securing means passing through all of the overlapped portions, the overlapped ends being at the point where the check strap is engaged by the picker stick.

JOHN C. CROCKER.
